UNITED STATES PATENT OFFICE.

OLAF INGVALD SAMDAL, OF MINNEAPOLIS, MINNESOTA.

BLOTTER-HOLDER.

SPECIFICATION forming part of Letters Patent No. 644,725, dated March 6, 1900.

Application filed October 7, 1899. Serial No. 732,946. (No model.)

To all whom it may concern:

Be it known that I, OLAF INGVALD SAMDAL, a citizen of the United States, residing at Minneapolis, in the county of Hennepin and State 5 of Minnesota, have invented a new and useful Blotter-Holder, of which the following is a specification.

This invention relates to blotting-pads, and has for its object to provide an improved 10 holder for detachable connection with different sheets of blotting-paper, so that the latter may be renewed when rendered useless from continued application or from any other cause.

15 It is furthermore designed to provide an improved handle for the convenient and ready manipulation of the blotting-pad.

To these ends the present invention consists in the combination and arrangement of 20 parts, as will be hereinafter more fully described, shown in the accompanying drawings, and particularly pointed out in the appended claim, it being understood that changes in the form, proportion, size, and minor details 25 may be made within the scope of the appended claim without departing from the spirit or sacrificing any of the advantages of the invention.

In the drawings, Figure 1 is a perspective 30 view of a blotting-pad constructed in accordance with the present invention. Fig. 2 is a longitudinal sectional view thereof, taken on the line *x x* of Fig. 1. Fig. 3 is a transverse sectional view taken on the line *y y* of Fig. 2.

35 Corresponding parts in the several figures of the drawings are designated by like characters of reference.

Referring to the accompanying drawings, 40 1 designates the body of the holder, which is preferably formed of a thin sheet of flexible celluloid, preferably of rectangular shape, as shown in the drawings; but it will be of course understood that any other shape may be employed as desired.

45 At opposite ends of the body and alined longitudinally intermediate of the opposite longitudinal edges thereof there are provided spring-clips 2, which are fixedly connected to the upper face of the body and have spring-

50 fingers 3, which embrace the adjacent edges and extend inward and substantially parallel with the under side of the celluloid sheet.

The sheet of blotting-paper 4 is cut to the size of the celluloid body and is fitted between the under side of the latter and the 55 upper sides of the spring-fingers, so that the blotting-sheet is detachably connected to the body of the holder.

For convenient manipulation of the blotting-pad there is provided a handle 5, which 60 is formed of stiff celluloid, rolled or twisted into the form of a cone, having a flat attaching-base 6, formed by one edge of the sheet, from which the handle is rolled or twisted. The attaching-base is glued or otherwise 65 secured flat against the upper face of the body and inclined transversely across the inner left-hand corner thereof when the blotter is placed in the position for use directly before the writer. As shown in Fig. 1, the larger 70 end of the rolled handle is located adjacent to the inner longitudinal edge of the body and the opposite smaller end is located adjacent to the left-hand end thereof, so as to be in convenient position for manipulation by 75 the left hand of the writer, thereby leaving the right hand free.

It will be noted that the main portion of the handle is formed into a spiral, which is located above the base thereof, so that the end of the 80 fingers of the operator may be passed beneath the body of the handle in order to obtain a firm hold thereon.

Extending the entire length of the outer longitudinal edge of the body is a metallic 85 strip 7, which is graduated to provide a ruler.

In using the present blotting-pad the handle 5 is held in the left hand, so that the right hand may be free for the purpose of writing, and the blotter may be applied immediately 90 after the writing has been finished. By having the handle increasing in diameter from the outer or left-hand end toward the inner or right-hand end a convenient shape for fitting the palm of the left hand is provided, 95 so that the handle may be firmly grasped.

It will of course be understood that it is designed to provide similar blotting-pads with the handle arranged at the right-hand side of the body, so as to accommodate the blotter 100 to persons who write with the left hand.

Having thus described the invention, what is claimed, and desired to be secured by Letters Patent, is—

A blotting-pad, having a blotting under surface, and a handle formed from a single sheet of stiff celluloid or like material, one end of the sheet being secured flat against the upper side of the pad, and forming an attaching-base, the main portion of the sheet being twisted or rolled into a conical-shaped spiral disposed above the attaching-base, and inclined across one inner corner of the pad, the larger end of the spiral being located adjacent to the inner longitudinal edge of the pad,

and the opposite smaller end extending toward the front of the adjacent transverse edge of said pad.

In testimony that I claim the foregoing as my own I have hereto affixed my signature in the presence of two witnesses.

OLAF INGVALD SAMDAL.
